ADJUSTABLE BROOM OR BRUSH

Christian Wildhaber, Mount Kisco, N. Y.

Application May 13, 1933, Serial No. 670,885

3 Claims. (Cl. 306—2)

This invention relates to adjustable brooms and brushes and refers more particularly to handle attachments for brooms, brushes and similar implements.

5 An object of this invention is the provision of a broom or brush which can be set at almost any position with respect to its handle, so that it can be used for sweeping, cleansing or washing the remotest corners of the floor or walls.

10 Another object is the provision of suitable means for adjusting the position of the stock or block of the brush with respect to the handle, and for securely locking said stock or block after having adjusted the same.

15 A further object is the provision of a broom or a brush having a handle which can be adjusted simultaneously in a vertical and a horizontal plane with respect to the block.

20 Still another object is the provision of a broom or a brush, having a handle, which can be adjusted in a vertical plane to the largest possible extent.

The above and other objects of this invention may be realized through the provision of a broom 25 having a holder, which is pivotally connected with a plate provided with grooves fitting into corresponding projections of another plate carried by the block of the brush; the holder may be provided with means cooperating with a member carried by the block or the first-mentioned plate for the purpose of preventing the holder from rotating around its pivot after an adjustment in the vertical plane has taken place.

The invention will appear more clearly from 35 the following detailed description when taken in connection with the accompanying drawing showing preferred embodiments of the inventive idea.

In the drawing:

40 Figure 1 is a side view of an adjustable broom. Figure 2 is a top view of the broom illustrated in Figure 1.

Figure 3 is a section along the line 3—3 of Figure 2.

The broom illustrated in Figures 1, 2 and 3 of the drawing comprises a wooden handle 10, which is inserted into a holder 11 and is connected with said holder by any suitable means not shown in the drawing.

45 A pivot 12 is used for connecting the holder 11 with a round plate or disc 13 provided with a plurality of grooves 14. As shown in Figures 1 and 2, the plate 13 is slightly curved, and the grooves 14 are formed on the lower surface of the plate 13. The bottom of these grooves projects in the form of ribs situated on the upper

surface of the plate 13, said grooves and ribs extending radially from the center of the plate to the edges thereof. The block 15 of the brush carries the bristles 16, which are attached to the block in any suitable manner. The block 15 carries also a plate 17, which is rigidly connected with the block by means of nails 27 or by any other suitable means. The plate 17 is similar in shape to the plate 13 and is provided with ribs 18 corresponding in size and shape to the grooves 14 formed on the plate 13. The ribs 18, situated on the upper surface of the plate 17, form the bottom of grooves situated on the lower surface of the plate 17. Due to this arrangement, the plates 13 and 17 may be used for locking the block 15 with respect to the holder 11 after the block has been rotated in a horizontal plane. The plate 13 is provided with a central opening 19, while the plate 17 has an opening 20 of the same size. The block 15 has a central bore 21 and carries a bolt 22, which passes through the bore 21 as well as through the central openings 19 and 20 of the plates 13 and 17, respectively.

The upper portion of the bolt 22 is provided 25 with screw threads 23 and carries a nut 24, as well as a washer 25. A coiled spring 26 is situated between the washer 25 and the plate 13 and is used for pressing the plate 13 against the plate 17. The force with which the spring 26 30 presses the plate 13 against the plate 17 may be varied by changing the position of the nut 24 on the bolt 22. If the operator finds that too much force is required for swinging the block 15 around the central axis of the bolt 22, he 35 will move the nut 24 somewhat further towards the upper end 31 of the bolt 22 and thus diminish the pressure exerted by the spring 26.

On the other hand, if the operator finds that the block 15 is not securely locked with respect 40 to the holder 11 and that the projections 18 of the plate 17 may snap out of the grooves 14 of the plate 13 while the broom is being used, he will move the nut 24 downwards along the screw threads 23 and thus further compress the 45 spring 26, increasing the pressure of said spring against the plate 13.

A resilient band or spring 28 is used for locking the holder 11 after it has been rotated around its pivot 12, and thus adjusted in a vertical plane. 50 This spring 28 is attached at one of its ends to the holder 11 by a bolt or screw 29, and is provided at its other end with a number of holes or openings 30, 30a, which are somewhat larger in size than the diameter of the bolt 22. The 55

upper end 31 of the bolt 22 may pass through any one of the holes 30, 30a. The spring 28 is preferably somewhat curved in shape to enable the end 31 of the bolt 22 to pass freely through 5 any one of the holes.

If the operator desires to adjust the handle of the broom in a vertical plane and, for instance, to move the handle 10 from the position shown in full lines in Figure 1 to the position shown 10 in broken lines in the same figure, he will raise the spring 28 until the end 31 of the bolt 22 comes out of the opening 30. As soon as the end 31 is disengaged, the holder 11 may be oscillated around the pivot 12 until the end 31 comes 15 opposite another one of the openings, for instance the opening 30a. Due to the resiliency of the spring 28, this spring will press against the end 31, while the holder 11 is being oscillated. As soon as an opening 30a comes opposite the end 20 31, the end 31 will pass through said opening, so that the holder 11 will be locked in a new position. By increasing the length of the spring 28 and the number of holes 30, 30a, formed therein, the number of the various positions, in 25 which the holder 11 can be locked, will be also increased.

As illustrated in Figure 1 of the drawing, the spring 28 is attached to the holder 11 close to the seam or joint 11a of the latter, while the 30 pivot 12 is connected with the tapered end 11b of the holder 11. Due to this arrangement, the holder 11 may form an angle of 90° with the vertical surfaces of the block 15.

What is claimed is:

35 1. A handle attachment comprising a holder, a plate pivotally connected with said holder, a block, a second plate rigidly connected with said block, the second-mentioned plate comprising projections adapted to snap into corresponding grooves formed in the first-mentioned plate; a bolt passing through a bore formed in said block, a nut carried by said bolt, a coiled spring surrounding said bolt and situated between said nut and the first-mentioned plate, and a member

carried by said holder at one end thereof and having a plurality of holes at its other end, an end of said bolt fitting into said holes.

2. A handle attachment comprising a holder having a tapered end, a plate, a pivot connecting the tapered end of said holder with said plate, a block, a second plate rigidly connected with said block, the second-mentioned plate comprising projections adapted to snap into corresponding grooves formed in the first-mentioned plate, a bolt 5 passing through a bore formed in said block, a nut carried by said bolt, a coil spring carrying said bolt and situated between said nut and the first-mentioned plate, a member having a plurality of holes at one end thereof, an end of 10 said bolt fitting into said holes, and means connecting the other end of said member with said holder, the last-mentioned means and said pivot being situated on opposite sides of said holder.

3. A handle attachment, comprising a holder, 20 a round plate pivotally connected with said holder, a plurality of radial grooves being formed in said plate, another plate having corresponding projections adapted to snap into said grooves, a block, the second-mentioned plate being rigidly connected with said block, a bolt passing through a bore formed in said block and through openings formed in said plates, the threaded end 25 of said bolt projecting beyond said plates and being adjacent to said holder, a nut carried by 30 said end of the bolt, a spring surrounding said end of the bolt and situated between said nut and the first-mentioned plate, and means connected with said holder for locking the same in one of a number of positions with respect to the 35 first-mentioned plate, said means consisting of a leaf spring fixedly connected to said holder and extending from said holder toward said round plate, said leaf spring being provided with a plurality of openings therein adapted to receive the 40 end of said bolt above said nut, and fix the holder in position relatively to the first-mentioned plate.

CHRISTIAN WILDHABER.
